METHOD AND APPARATUS FOR
DEPOSITING TOW

John T. Burns, Ayden, N.C., assignor to E. I. du Pont de Nemours and Company, Wilmington, Del., a corporation of Delaware

Filed Feb. 3, 1960, Ser. No. 6,545

2 Claims. (Cl. 28—21)

This invention relates to methods and apparatus for handling rapidly moving filamentary material, and is concerned especially with the delivery of textile tow material in orderly arrangement.

Methods and apparatus have been previously described for depositing continuous filamentary material such as yarn on a support by blowing the yarn through a tube revolving about an axis passing through one end of the tube to deposit the yarn in the form of piled or overlapping loops or coils. However, when attempts were made to use these previously known procedures for handling tow, i.e., large bundles of substantially continuous filaments, difficulty was encountered with the entanglement of filaments making up the tow bundle. Furthermore, when the procedure was used as a method of collecting undrawn synthetic fibers, it was discovered that during the subsequent drawing operation non-uniformly drawn sections were developed in the tow which led to non-uniform dyeing in fabrics prepared from the drawn fibers.

A primary object of the present invention is the provision of a method of controlling the delivery of a rapidly moving textile tow so that it is deposited upon a surface without the formation of looped or entangled filaments. A further object is the provision of a controlled method of depositing an undrawn synthetic fiber tow into a receptacle in a relaxed state in such a manner that the filaments of the tow bundle remain essentially parallel. These and other objects of this invention, together with means and methods of accomplishing the various objects, will be apparent from the following description and the accompanying drawings.

The objects of this invention are accomplished, with large tows of 10,000 to 500,000 total denier travelling at high speeds of 500 to 2500 yards per minute, by feeding the tow in a downward direction to fluid jet forwarding means arranged to discharge the tow outwardly at an angle of 30° to 75° to the original downward direction of feed while revolving about the feed to deposit the tow in a helical coil on a support, provided that the operation of the fluid jet is controlled within narrow limits which involve critical relationships between the denier of the tow, the speed at which the tow is fed, the area of the minimum cross section of the jet stream, the static pressure of the gas forming the jet stream and the flow of gas. It has been found that a surprising improvement in the operation is accomplished by critical control of these variables and that the entanglement of filaments previously encountered when handling tows of synthetic fibers at high speeds can be substantially eliminated.

In the drawings, which illustrate preferred embodiments of the invention,

Figure 1 is a plan view partly in section showing a specific embodiment of an apparatus useful for carrying out the invention,

Figure 2 is an enlarged view of a preferred embodiment of the jet forwarding means 5 of Figure 1,

Figure 3 is a graph illustrating the preferred internal

2

cross section index of the jet forwarding means for various sizes of tow bundles, and

Figure 4 is a graph illustrating the relationship between the preferred fluid pressure and the speed of the tow bundle.

As used herein the word "tow" refers to a bundle of substantially continuous filaments.

Now referring to Figure 1, tow bundle 1, which may be obtained directly from a synthetic fiber spinning machine, is passed over forwarding pulley 2 and then in a downwardly direction into confining tube 3. The tow then passes around pulley 4, making an angle between about 30° and 75° with the initial downward path of travel, and is then passed through jet forwarding means 5. Air or other inert compressed gaseous fluid is passed into pressure tube 6 through throttling valve 7, to provide the desired pressure as indicated on gage 8, and enters the rotating part of the apparatus through sliding hollow collar 9. The compressed gaseous fluid is then passed through gas tube 10 into jet forwarding means 5 where it is brought into contact with the tow bundle. The whole assembly of parts 3, 4, 5, and 10 is rotated about an axis through the center of vertical tube 3 by means of a pulley, not shown, to discharge the tow in the form of a helical coil in collection drum 11.

Figure 2 shows the construction of a preferred jet forwarding means. The tow bundle enters the jet through inlet tube 12 projecting into foretube 13. The tow passes from the inlet tube into the foretube and through throat 14 which is the point of minimum diameter of the foretube. Compressed gaseous fluid is supplied through gas tube 10 to plenum chamber 15 from where the gas is discharged into the foretube through annular opening 16 formed between the outside of inlet tube 12 and the inside of the inlet end of the foretube. The chamber surrounds the inlet tube and the end of the foretube, with thread engagement being provided with the inlet tube at 17 and the foretube at 18, so that the relative positions of the tubes can be adjusted to vary the size of the annular opening 16. The tow passes through the inlet tube, which should be of suitable size to accommodate the tow without excessive back-flow of gas, and into the foretube to be pulled along by the forwarding action of the jet formed by the gas discharging through the throat. In order to provide for an efficient flow of gas, the foretube tapers outward gradually from the throat in the direction of tow travel at a divergence angle 19, which is suitably from 15 minutes to 3°, and may also flare outward towards the inlet end at an angle 20 which may be up to 10°.

It has been found that there is a critical relationship between the cross-sectional area of the throat 14 and the denier of tow which can be handled without entangling of filaments. For example, a jet having a throat diameter of 0.500 inch or cross-sectional area of 0.196 square inch is suitable for handling tow of 125,000 to 300,000 total denier, measured in grams per 9000 meters, travelling at speeds of 500 to 2500 yards per minute when the static pressure of the gas and the flow of gas through annular orifice 16 are critically adjusted as disclosed hereinafter. This jet forwarding means may suitably have an internal inlet tube diameter of about 0.420 and a foretube length, measured from the end of the inlet tube at 21 of 14 to 22 times the throat diameter. The angle of divergence 19 in the tow direction is suitably 15 minutes to 3° and that of the angle 20 in the other direction from the throat, 0° to 10°. Taking this jet forwarding means as a basis for comparison, the relationship between tow denier and satisfactory throat cross-sectional areas is shown in Figure 3. In this graph a jet index number of $J=1.0$ means that the cross-sectional

area of the throat is 0.196 square inch and $J=0.8$ indicates an area of $(0.8)(0.196)=0.157$ square inch. The graph indicates that, for any given denier of tow, the cross-sectional area of the throat must be within the range of $J=0.00222\sqrt{D}-0.22$ and

$$J=0.00388\sqrt{D}-0.37$$

where D is the tow denier in grams per 9000 meters. In general, the jet stream must have a minimum cross-sectional area (A) in square inches, i.e., at the throat, which is numerically equal to a value within the range defined by $0.000435\sqrt{D}-0.043$ and $0.000760\sqrt{D}-0.072$ where D is the total denier of the tow to be conveyed.

The size of the annular opening 16 must be adjusted within critical limits to give the proper flow of gas for the particular cross-sectional area of jet throat. Therefore, this adjustment is also interrelated with the denier of tow to be conveyed. Since actual measurement of the internal clearances is difficult, it is more convenient to determine the setting which will provide a specified flow in standard cubic feet per minute (s.c.f.m.) when tested with air supplied at a static pressure of 60 pounds per square inch gage (p.s.i.g.) without tow in the jet. Proper adjustment under these conditions is a setting that will pass an amount of air in s.c.f.m. which is numerically equal to $(160\pm28)\sqrt{A}$ where A is the cross-sectional area of the throat in square inches.

If it is desired to use a gas pressure other than 60 p.s.i.g. for the adjustment of the internal clearance of annular opening 16, the correct gas flow is approximately equal to

$$(160\pm28)\sqrt{A}\left(\frac{P+15}{75}\right)$$

standard cubic feet per minute where P is the static pressure in p.s.i.g.

In actual operation the static gas pressure can be from 26 to 163 pounds per square inch gage, dependent upon the speed at which the tow is fed through the jet. The critical relationship between the static gas pressure and the tow speed is shown in Figure 4. The tow speed must be numerically equal to a value within the area defined by $313\sqrt{P}-1491$ and $313\sqrt{P}-1097$ for tow speeds ranging from 500 to 2500 yards per minute. When the process of this invention is operated under conditions falling within the area bounded by the two lines drawn on the graph, a remarkable reduction in filament entanglement is achieved. Conversely, when the process is operated under conditions falling outside of the area bounded by the two lines in the graph of Figure 4, an excessive amount of filament entanglement and loop formation is observed. Since methods of controlling gas pressure are well known in the art, no specific method will be described here.

It is to be recognized that an important feature of the process of this invention is the placement of the jet forwarding means at the delivery end of the rotatably mounted apparatus. Attempts have been made to place the jet forwarding means in the vertical path of travel of the tow bundle, upstream from the outward turn made by the tow before it is discharged into the atmosphere, but operation in such manner always leads to an excessive amount of filament entanglement.

It is a requisite of this invention that both the internal dimensions of and the pressure of the fluid supplied to the jet forwarding means fall within the prescribed limits. If either of these parameters fall outside of the limits described herein, the advantages of the invention are not obtained.

The following examples further illustrate specific embodiments of this invention:

EXAMPLE I

Apparatus for the delivery of tow is set up as shown in Figure 1. The jet forwarding means 5 has a jet index of 1.0, i.e., the internal diameter of the inlet tube 12 is 0.420 inch and the internal diameter of the foretube throat 14 is 0.500 inch. The internal angle 20 between the diverging foretube walls at the inlet is 8° and the angle 19 downstream of the throat is $1^\circ 30'$. The jet annular opening 16 is set to deliver 72.7 s.c.f.m. at 60 p.s.i.g. with no tow in the jet. Compressed air is applied to the jet forwarding means at 35 p.s.i.g. The angle of the delivery tube is set at 47° from the vertical, and the shaft is rotated at about 225 r.p.m. The delivery tube is positioned about twelve inches above the top of a collection drum, which is sixty inches in diameter and sixty inches high. The drum is rotated at 3 r.p.m., the center of the drum being offset nine inches from the axis of rotation of the delivery apparatus.

Undrawn polyethylene terephthalate fiber tow approximating 195,000 denier (roughly 43,000 individual filaments) is fed to the apparatus at 830 yards per minute using conventional forwarding apparatus and guides, and deposited in the drum in overlapping loops. When the tow is subsequently withdrawn from the drum for further processing on a drawing apparatus, it is discovered that the number of draw machine stops due to entangled filaments is less than 0.10 stop per thousand pounds of tow processed. Furthermore, when the drawn tow is cut into staple, spun into yarn, woven into a fabric and dyed, the number of dyeing defects due to undrawn yarn sections is less than about 0.7 per square yard of fabric.

When the procedure of Example I is repeated using a jet forwarding means having a jet index number as defined in connection with Figure 3 of 1.5 and an air pressure of 60 p.s.i.g., it is found that the number of draw machine stops because of entangled filaments in the tow is about 0.35 stop per thousand pounds. Dyed fabric prepared from the tow exhibits an average of 3.5 defects per square yard.

In like manner, when the procedure of this example is repeated using jet forwarding means having an index number of 0.60, and with air supplied at 40 p.s.i.g., an excessive number of entangled filaments is encountered with non-uniform delivery. Further, fabric prepared from the tow exhibits an excessive level of dyeing defects.

EXAMPLE II

The procedure of Example I is repeated with the exception that the tow bundle has a total denier of 79,500, and is fed to the delivery apparatus at a rate of 1600 yards per minute. The jet forwarding means of the delivery apparatus has a jet index number of 0.5 and is supplied with air at 86 p.s.i.g. The jet annular opening has been set to deliver 46 s.c.f.m. at 60 p.s.i.g. Tow is delivered into a drum as previously described. The jet is rotated at the rate of 435 r.p.m.

When the tow is removed from the drum for drawing, it is found that the number of draw machine stops because of entangled filaments is less than 0.1 stop per one thousand pounds. Dyed fabric prepared from the tow exhibits a defect level of about 0.6 defect per square yard.

When the procedure of Example II is repeated with a jet forwarding means having a jet index number of 1.0 and with air supplied at 55 p.s.i.g. (outside the critical limits as defined in this invention for the tow speed used) it is found that the number of draw machine stops due to entangled filaments is approximately 0.5 stop per thousand pounds. Processing of the tow into dyed fabric yields fabric having approximately 4.0 defects per square yard.

In like manner, when the procedure of this example is repeated with a jet forwarding means having an index number of 0.30 and with air supplied at 75 p.s.i.g., it is found that the system is not operable.

EXAMPLE III

The procedure of Example I is repeated with the exception that the tow bundle has a total denier of 251,000 (approximately 12,000 filaments) and is fed to the delivery apparatus at a rate of 789 yards per minute. The jet forwarding means 5 of the delivery apparatus has an index number of 1.15, which corresponds to an inlet tube diameter e of 0.448 and a foretube throat diameter of 0.536. Air is supplied to the jet forwarding means at a pressure of 42 p.s.i.g. The tow is deposited in overlapping loops in a drum as previously described.

When the tow is removed from the drum for drawing, it is found that the number of draw machine stops attributable to entangled filaments is less than about 0.1 stop per thousand pounds. When the tow is processed into staple fiber, spun into yarn, woven into a fabric, and dyed, it is found that the dye defect level is approximately 0.5 defect per square yard.

When the procedure of Example III is repeated with a forwarding means having an index number of 0.75 and with air supplied at 55 p.s.i.g., it is found that the system is not operable.

Similarly, when the procedure of Example III is repeated with a jet forwarding means having an index number of 1.50 and air supplied at 60 p.s.i.g., an excessive number of entangled filaments is encountered.

EXAMPLE IV

Following the general procedure of Example I, polyethylene terephthalate tow is delivered under various combinations of conditions as described in Table I below. The number of draw machine stops attributable to entangled filaments as well as the number of dyeing defects in fabric prepared from the drawn fiber, listed in the table, clearly indicate the criticality of the process conditions defined in the appended claims.

Table I

Run No.	Tow, Denier	Tow Speed, y.p.m.	Jet Index	Air Pressure, p.s.i.g.	Jet Rotation Speed, r.p.m.	Entanglement Stops	Fabric Dye Defects
1	195,000	830	0.5	70	230	inoperable	
2	195,000	830	0.75	40	230	0.4	6.0
3	195,000	830	1.0	40	230	0.08	0.7 0.7
4	195,000	830	1.5	50	230	0.35	7.0 7.0
5	132,000	1,600	0.4	86	420	inoperable	
6	132,000	1,600	0.75	86	420	0.05	0.6 0.6
7	132,000	1,600	1.15	60	420	0.30	3.2
8	132,000	1,600	1.27	55	420	0.37	3.5
9	79,500	1,600	1.27	55	435	0.55	4.5
10	38,200	1,600	0.35	77	415	0.09	
11	38,200	1,600	0.5	85	415	0.80	
12	38,200	1,600	1.0	55	415	1.28	

Although the process of this invention has been described with particular reference to the handling of polyethylene terephthalate tow, it is to be understood that the advantages of the process accrue to the handling of other types of polyester tows as well as to tows prepared from other synthetic polymers such as the polyamides, polyurethanes, the acrylics and other vinyl types, and to tows prepared from cellulose derivatives.

The present invention provides an improved method of depositing a synthetic fiber tow in a pile or a heaped coil in a relaxed state in such a manner that the tow can be withdrawn from the pile without encountering an excessive number of entangled filaments. Furthermore, the filaments are maintained in substantially parallel relationship with each other across the tow bundle so that when tension is subsequently applied to the tow bundle, the tension is distributed evenly among the filaments making up the bundle. The apparatus described for the carrying out of the method of this invention exhibits a greatly reduced abrasive effect upon the filaments of the tow being processed in comparison with other types of tow delivery apparatus.

The preferred fluid for the operation of the jet forwarding means 5 of Figure 1 is air, although other gases may be used with equal effect. Minor amounts of reactive vapors may be included in the gas stream, if chemical treatment of the filament surfaces is desired.

Although the specific embodiments described in the examples have referred to the deposition of the tow into a circular drum, the invention may also be used for depositing the tow upon a flat surface or upon a moving conveyor belt.

Since many different embodiments of the invention may be made without departing from the spirit and scope thereof, it is to be understood that the invention is not limited by the specific illustrations except to the extent defined in the following claims.

I claim:

1. In a process for temporarily depositing a rapidly moving tow of substantially continuous filaments in a relaxed state on a support by feeding the tow in a downward direction to a tubular passageway directed outwardly at an angle of 30° to 75° to said downward direction, conveying the tow through said passageway with a stream of gas and discharging the tow onto a support while revolving the point of discharge about said downward direction of feed to deposit the tow in a helical coil on the support, the improvement for depositing a pile of relaxed tow from which the tow can subsequently be withdrawn without substantial entangling of filaments which comprises introducing into said passageway a jet stream of gas having a minimum cross-sectional area (A) in square inches which is numerically equal to a value within the range defined by $0.000435\sqrt{D} - 0.043$ and $0.000760\sqrt{D} - 0.072$ where D is the total denier of the tow to be conveyed, supplying the gas to form said jet stream under a static pressure of 26 to 163 pounds per square inch gage at a rate of flow in standard

cubic feet per minute which, in the absence of tow, is numerically equal to

$$(160 \pm 28)\sqrt{A} \left(\frac{P+15}{75} \right)$$

where P is the static pressure of the gas and A is as defined above, and feeding tow of from 10,000 to 500,000 total denier into said passageway with the jet stream at a speed in yards per minute which is numerically equal to a value within the range defined by $313\sqrt{P} - 1491$ and $313\sqrt{P} - 1097$ where P is the static pressure of the gas.

2. In an apparatus for depositing a rapidly moving tow in a helical coil on a support including means for feeding the tow in a downward direction to a tow depositing tube directed outwardly at an angle of 30° to 75° to said downward direction and means for revolving the discharge end of said tube around an axis corresponding to said downward direction of feed, tow forwarding means located at the entrance of said tube comprising a jet tube having a minimum throat cross-sectional area in square inches which is numerically equal to a

value within the range given by $0.000435\sqrt{D}-0.043$ and $0.000760\sqrt{D}-0.072$ where D is the total denier of the tow and D is from 10,000 to 500,000 denier, said jet orifice tapering outwardly from said throat at an angle of from 15 minutes to 3° in the direction of tow travel and at an angle of 0° to 10° in the inlet end direction, a tow feeding tube projecting into the inlet end of said jet tube, a gas chamber surrounding said tow feeding tube and opening into the inlet end of said jet tube, means for supplying gas to said chamber at a pressure of 26 to 163 pounds per square inch gage, means for adjusting the flow of gas into said jet tube to $(160\pm28)\sqrt{A}$ standard

10

cubic feet per minute, where A is said cross-sectional area of the throat and the flow is determined with air at 60 pounds per square inch gage pressure without tow in the jet tube, and means for feeding tow to said feeding tube at a speed in yards per minute which is numerically equal to a value within the range given by $313\sqrt{P}-1491$ and $313\sqrt{P}-1097$ where P is the pressure of gas in said gas chamber in pounds per square inch gage.
